Primary Examiner — Holly E Thurman*Assistant Examiner* — Altaira J Swangin(74) *Attorney, Agent, or Firm* — QuickPatents, LLC; Kevin Prince(57) **CLAIM**

The ornamental design for a cake drum, as shown and described.

DESCRIPTION

FIG. 1 is a top perspective view of a cake drum, showing my new design;

FIG. 2 is a bottom perspective view thereof;

FIG. 3 is a top plan view thereof;

FIG. 4 is a bottom plan view thereof;

FIG. 5 is a front elevational view thereof, the rear elevational view, left-side elevational view, and right-side elevational view all being identical thereto; and,

FIG. 6 is a partial section view taken along the cut line 6-6 as indicated in FIG. 3.

The dash-dot broken lines in FIG. 3 represent the section cut of the partial section view in FIG. 6 and form no part of the claimed design. The dash-dot broken lines in FIG. 6 represent the boundary line of the partial section view and form no part of the claimed design.
